OSCILLATOR TUBE AND CIRCUIT

Gerard J. Lehmann, New York, N. Y., assignor
to Federal Telephone and Radio Corporation,
New York, N. Y., a corporation of Delaware

Application October 28, 1944, Serial No. 560,769

6 Claims. (Cl. 315—39)

1

This invention relates to vacuum tube oscillators and their associated circuits of the type in which energy is fed back to the grid circuit through the interelectrode tube capacities.

Ordinarily in oscillators of the type referred to hereinabove, the mode of oscillation is such that the grid and plate voltages are 180° out of phase and a relatively large high frequency grid current flows. In order that such oscillators should operate efficiently, it is essential that the grid or grids be connected to the outside of the tube by leads offering low impedance to the high frequency currents. Such low impedance leads introduce serious problems in design and manufacture.

In accordance with the present invention, I have found that by producing a mode of oscillation in which the grid and plate voltages are in phase, and by proportioning the parameters of the tube and its associated circuits, as is described hereinafter, the grid or grids carry no high frequency current, and therefore the grid leads to not have to be of low impedance but merely have to be adequate to carry the D. C. potentials.

An object of the present invention is the provision of an improved vacuum tube for the purpose hereinabove described.

Another object of the present invention is the provision of an improved vacuum tube oscillator in which the grids carry no high frequency current.

A further object of the present invention is the provision of an improved vacuum tube oscillator of the type hereinabove described in which no low impedance grid leads are required and in which the leads to the grid only have to carry direct current thereto.

In accordance with my invention, I obtain the desired mode of oscillation in which the plate and grid oscillate in phase by feeding back energy through the interelectrode capacity of the tube. This energy may be fed back through any means known in the art, such as for example, by the use of a tuned plate circuit. In order to obtain this mode of oscillation, the electron transit angle should be 180° at the frequency at which said tube is designed to oscillate. Such tubes are designed to operate at a relatively narrow band of frequencies and the closer the electronic transit angle is to 180° at the frequency selected, the greater will be the efficiency obtained from this mode of oscillation. In this mode of oscillation the cathode and anode potentials are out of phase and therefore the currents

2

flowing through the capacities anode to grid and filament to grid are in opposition and consequently the grids will draw no current if the parameters of the tube and circuit are selected such that

$$V_{gc} \times C_{gc} = V_{ga} \times C_{ga}$$

where

V_{gc} is the high frequency potential drop between the grid and cathode

V_{ga} is the high frequency potential drop between the grid and anode

C_{gc} is the capacity between the grid and cathode and

C_{ga} is the capacity between the grid and anode.

In accordance with this invention, where more than one grid is employed, the grid facing the anode and the grid facing the cathode are coupled by means of a relatively high capacity inside the tube so that said grids are at the same high frequency potential. The grid referred to in the above terms C_{cg} then is the grid facing the cathode and the grid referred to in the term C_{ga} is the grid facing the anode. Since both grids would be at the same high frequency potential being coupled together, it does not matter in the terms V_{gc} and V_{ga} which grid is considered.

Other and further objects and advantages of the present invention will become apparent and the foregoing will be best understood from the following description of an embodiment thereof, reference being had to the drawing, in which Figure 1 is a longitudinal sectional view of a vacuum tube oscillator and an associated circuit embodying my invention and Figure 2 indicates the 180 degree out of phase relation of cathode and anode voltages.

Referring to the drawing, the general structure of the tube 1 is in some respects similar to that of the tubes disclosed in my copending applications, Serial No. 441,105 filed April 30, 1942, and patented June 25, 1946, as Patent No. 2,402,602, and Serial No. 474,085, filed January 30, 1943 and patented July 8, 1947, as Patent No. 2,423,819 and is a beam type tetrode in which the second grid focuses the beam. The insulating portions of the tube envelope consist of a portion 2, of the shape indicated, through which cathode support members 3, 4, and 5 pass and through which they are sealed. The supports 3 and 5 are also employed as current-carrying leads heating the filamentary cathode 6 which is preferably, but not necessarily, of the double spiral type. The member 4 supports the far end of the spiral cathode, as shown.

The anode electrode may be formed from a solid block of metal 7, preferably copper. A suitable knife edge is formed on the outside of the block to seal it to the end of the insulating portion 2 as indicated at 8, and thus complete the tube envelope. The active portion of the block or the anode which receives the electron current from the cathode is a cylindrical surface 9 which may be formed by boring a hole in the end of the block.

Heat dissipation from the anode may be facilitated by boring a central cavity 10 in that portion of the block which is exterior to the tube envelope and cutting radial grooves from said cavity 10 into the block. An air blast directed into the cavity and thence through the grooves dissipates the heat which flows into the fins existing between the grooves.

The tube is provided with two grid electrodes 11 and 12, of which grid 12 serves to focus the electron beam. Said grid electrodes 11 and 12 consist of a plurality of parallel bars welded at their upper ends to cone-shaped metallic members 13 and 14, respectively, members 13 and 14 being supported by any suitable means such as glass beads 15 from the top of insulating portion 2. Conical members 13 and 14 are arranged close to each other and have a relatively large surface area so that a high capacity is formed therebetween connecting the two grids. Cones 13 and 14 and consequently grids 11 and 12 are connected externally by means of leads 16 and 17 passing through and sealed in the insulating portion 2 of the envelope and connected inside the envelope to cones 13 and 14. In accordance with my invention, these leads do not have to be low impedance leads but preferably are leads sufficient to carry the D. C. potentials which are applied to the respective grids and are of high impedance at the frequencies at which said tube is designed to oscillate.

The oscillatory circuit associated with said tube is arranged as follows:

An inner conductive cylinder 18 is connected to cathode support member 4 and consequently to the cathode, cathode support members 3 and 5 passing through the interior of said cylinder. Tube 1 and cylinder 18 are mounted within a large outer conductive cylinder 19. A cylinder 20, similar to 18, is connected to the portion of the anode block exterior to the tube and is likewise mounted within cylinder 19. The electrical length from the end of cylinder 20 to the opposite end of anode 9 is preferably substantially half a wavelength at the operating frequency of said device. A shorting plunger 21 is arranged between cylinder 18 and cylinder 19 and is adapted to be moved to tune the anode to cathode circuit. The cylinders may be considered as forming a resonant cavity chamber tuned by shorting plunger 21.

The high frequency oscillatory energy of this system may be derived as output in various ways known in the art. For this purpose, in the embodiment illustrated, an output coupling loop 22 is inserted through an opening in cylinder 19.

The direct current connections to the grids may be made by passing leads 16 and 17 through suitable openings in cylinder 19 and connecting them to D. C. sources. Likewise the D. C. potential for the anode may be supplied by a line 23 passing through a suitable opening in cylinder 19 and connected to the portion of the anode block exterior to said envelope, the other end of said line 23 being connected to a positive source of D. C. anode potential.

It will be seen that in the system shown the feedback is made through the interelectrode capacities and that this is accomplished by tuning the anode-cathode circuit. Grids 11 and 12 are maintained at the same high frequency potential because of the relatively high capacity between members 13 and 14. In order to obtain the mode of oscillation hereinbefore mentioned, that is, the potentials of the grids and anode being in phase, the electronic transit angle is made substantially equal to 180°, or stated in another way the electron transit time is equal to half the period of a complete oscillation at the operating frequency of the system. This is accomplished, as is known in the art, by suitably spacing the anode and cathode and applying proper potentials therebetween. Moreover in order to maintain the grids at the null potential point relative to the instantaneous anode and cathode potentials so that the grids carry no high frequency currents, the parameters of the circuit are selected such that the product of the instantaneous alternating current voltage and the capacity between cathode 6 and grid 11 is equal to the product of the instantaneous alternating current voltage and capacity between grid 12 and anode 9. By adjusting the D. C. potentials applied to the anode, grids, and cathode in relation to the interelectrode capacities, this condition is readily fulfilled.

While I have described the tube as being a tetrode, my invention may also be employed with triodes or other multi-element tubes. Furthermore, while I have shown one type of circuit associated with said tube, it is obvious that various other forms of circuits depending for their oscillation on the feedback of energy through their interelectrode tube capacities may be employed.

Accordingly, while I have described above the principles of my invention in connection with specific apparatus, it is to be clearly understood that this description is made only by way of example and not as a limitation on the scope of my invention as set forth in the objects of my invention and the accompanying claims.

45 I claim:

1. In a vacuum tube oscillator, the combination according to claim 4 wherein the means for feeding energy back to the cathode includes a tuned anode-cathode circuit.

50 2. In a vacuum tube oscillator, the combination according to claim 4 wherein the means for feeding back energy to the cathode includes a tuned cavity resonator interconnecting the anode and cathode.

55 3. In a vacuum tube oscillator, the combination according to claim 4 wherein the means for feeding back energy is comprised of a conductive cylinder connected to the cathode, a conductive cylinder connected to the anode, a larger cylinder surrounding said cathode and anode cylinders and capacitively coupled thereto, and movable shorting means connected between said larger cylinder and one of the other cylinders.

60 4. A vacuum tube oscillator comprising a vacuum tube having a cathode first and second grids, and an anode mounted in the order named, means arranged between said grids for providing large capacitance therebetween at an operating frequency to maintain said grids at the same high frequency potential, means coupled between said anode and cathode and including the interelectrode capacities for providing a feedback path from said anode to said cathode having a 180° phase shift at the operating frequency, the dimensions of said tube being such that the electron

transit time between said cathode and said anode is substantially equal to half a period at the operating frequency, said grids presenting high impedance at the operating frequency of said oscillator compared to the impedance offered by said capacitance between said grids.

5. A vacuum tube oscillation according to claim 4 wherein the parameters of said tube are such that they satisfy the further relation

$$V_{gc} \times C_{gc} = V_{ga} \times C_{ga}$$

where

V_{gc} is the alternating current voltage between grid and cathode,

V_{ga} is the alternating current voltage between grid and anode,

C_{gc} is the capacity between grid and cathode, and

C_{ga} is the capacity between grid and anode.

6. A vacuum tube oscillator according to claim

4 in which said means for providing large capacitance comprises concentric cones, one connected to each of said grids and mounted closely adjacent one another.
